COAL STOKER

Earl A. Strang, Waukegan, Ill.

Original application February 19, 1943, Serial No. 476,478. Divided and this application March 19, 1945, Serial No. 583,622

2 Claims. (Cl. 110—46)

This application is a divisional application of the original application Serial No. 476,478, filed February 19, 1943, on Coal stoker.

This invention relates to a coal stoker.

Among the objects of my invention is to provide a coal stoker in which the coal is directly and positively moved by a plunger head to the fire pit without the coal contacting or interfering with any other part of the driving mechanism. Another object is to provide a stoker in which the driving mechanism performs the triple function of feeding the coal, co-operating with a ratchet mechanism to shake the hopper and co-operating with an agitator to keep the exit tube clear of obstruction.

Another object is to create a stoker in which the exit tube is positioned between the fire pit and the hopper so as to provide an exit to prevent the gases from reaching the hopper and causing combustion therein and from reaching and interfering with the stoker mechanism. My invention contemplates such other objects, advantages and capabilities as will later more fully appear and which are inherently possessed by my invention.

While I have shown in the accompanying drawings a preferred form of my invention, yet I wish it understood that the same is susceptible of modification and change without departing from the spirit of my invention.

Referring to the drawings, Fig. 1 is a side elevational view of my stoker; Fig. 2 is a top plan view of the same with the hopper removed; Fig. 3 is a detailed sectional view of the hopper and tube construction; and Fig. 4 is a top plan view in section to show operating parts in related positions.

The embodiment selected to illustrate my invention comprises a burning pit or retort 10, receiving one end of a hollow pipe or tube 11.

A bearing or hopper support casting 12 is attached to said tube 11 and has an opening 13 communicating with an opening 14 in the tube. The casting 12 has a top flange 15 on which is mounted a filler ring 16 about which is positioned a pawl ring 17, having an ear 18. A rotatable ratchet member 19 has a circumferential groove 20 to receive filler ring 16. The ratchet member 19 has a plurality of ratchet teeth 21. A pawl housing 22 having a pawl 23 is pivotally attached to ear 18 of pawl ring 17. The casting 12 extends upwardly on an angle as shown at 24 so that hopper 25 attached to ratchet member 19 extends diagonally upwardly. The bolts 26 attaching

hopper 25 to ratchet member 19 may be removed and hopper 25 tilted on hinge 27.

The tube 11 extends from the retort 10 to the gear box 28. Movable within tube 11 is a plunger 29 having a shoulder head 30 at one end, and a pair of oppositely disposed lugs 31 adjacent its other end. Plunger 29 is hollow and within its interior, screw 32 is fixed with one end of said screw attached within shoulder head 30. A driving tube 33 has a threaded portion 34 fitting around the free end 35 of the plunger screw 32. Driving tube 33 is, of course, hollow to the extent of screw 32 so as to accommodate the same. Extending beyond the driving tube 33 is a driving gear 34. A jack shaft 35 with three gears transmits motion from motor 36, through belt driven worm gearing 37 to reversing clutch shaft 38 and intermediate pinion gear 39 to driving gear 34 and thence to plunger screw 32. The driving mechanism may be controlled by suitable switch or thermostat means (not shown) so as to provide desired back and forth movement of the plunger 29.

A ratchet pull rod 40 is slidably mounted in bearings 41 attached to tube 11, and has eye 42 at one end for the attachment of cable 43, and a stop pin 44 adjacent its other end. The cable 43 extends through pulley 45 bracketed to tube 11, and then to the pawl housing 22. A draw spring 46 extends between the pawl housing 22 and an anchor bolt 47 which is attached to casting 12. An arm 48 is attached to pull rod 40.

A gas vent rod 49 is slidably mounted through an opening in the lower portion of arm 48, and has a stop member 50 therebeyond. Said rod 49 is coupled to bell crank 51, which extends into escape gas flue 52 and has therein a pair of agitators 53.

The escape gas flue 52 is located between the retort 10 and the hopper 12 to prevent exhaust gases from reaching the hopper and other parts of the mechanism and has a stub for the attachment of suitable smoke exit means.

Tube 11 has a pair of oppositely disposed slots 54 adapted to slidably receive spaced lugs 31.

Near each of the opposite ends of the feed stroke are positioned resilient shift arms 55, which are adjustably attached to shift rod 56 which is attached at one end to a bearing 57 in the gear housing 28, and at the other end to a bearing 58 attached to the casting 12. Within gear housing 28 a shifting fork 59 is attached to shift rod 56 and operates a clutch 38 for reversing direction of the plunger 29; adjacent the outer end of shift rod 56 are a plurality of detents 60

to receive spring plunger 61 positioned in bearing 57 to hold shift rod 56 from moving out of desired position.

A wind blower 62 is provided with a duct 63 leading into shroud 64 surrounding fire pit 10.

In use, coal is placed in the open upper end 75 of hopper 25 and falls by gravity as it is used through openings 13 and 14 into tube 11. Adjustable shift arms 55 having been set as desired, and the motor 36 having been turned on, at the desired time, plunger 29 moves forwardly, contacts the coal which has dropped into tube 11 and pushes it ahead into the fire pit 10. Near the end of the feed stroke one of lugs 31 strikes against one of the resilient shift arms 55 to move shift rod 56 and shifting fork 59 so as to engage clutch 38 and provide reverse movement of the plunger 29.

On the return or idle stroke a lug 31 strikes arm 48 to move pull rod 40 and cable 43 so that pawl 23 engages a tooth 21 of ratchet plate 20 and moves it for a distance of about one tooth. This turns the hopper, and prevents clogging of the same, thereby providing an even and full supply of coal; it being noted that at the time that the hopper is shaken, the plunger 29 is ready to free openings 13 and 14 for the ready reception of coal by the tube 11.

At the same time that lug 31 strikes arm 48 and actuates the hopper shaking mechanism, the arm 48 is moved on gas vent rod 49 until it hits stop member 50. This provides a slight delay in moving rod 49, bell crank 51 and agitators 53 within escape gas flue 52. The agitators prevent clogging of the escape gas flue 52 with sooty particles and clears the passage of gaseous fumes.

Near the end of the stroke lug 31 contacts the opposite resilient shift arm 55 for again reversing the direction of travel of the plunger 29.

Having thus described my invention, I claim:

1. In a stoker, having a fire pit, a tube having one end extending into said fire pit, a hopper rotatably mounted on said tube and communicating therewith, a plunger within said tube, adjustable and automatic means for driving said plunger back and forth within said tube, an

escape gas flue attached to and communicating with said tube between said fire pit and said hopper, a pull rod slidably attached to said tube, a cable attached to said pull rod, ratchet means in communication with said cable, said ratchet means mounted on said hopper, an arm attached to said pull rod, a gas vent rod attached to said arm, a bell crank pivotally attached to said vent rod, an agitator attached to said bell crank and extending within said escape gas flue, said tube having a slot, said plunger having a lug extending through said slot, said lug upon rearward movement of said plunger contacting said arm said arm moving said pull rod, cable and ratchet means to slightly rotate said hopper, said arm also moving said gas vent rod and bell crank to actuate said agitator within said escape gas flue.

2. In a stoker, having a horizontal tube, a hopper mounted on said tube and communicating therewith, a hollow covered plunger of slightly less diameter than said tube, said plunger slidably within said horizontal tube, a screw completely positioned within said plunger, a shoulder head attached to the front end of said screw 25 said shoulder head forming the front end of said covered plunger, a driving member within said tube and having a screw threaded nut for engaging said screw, means for actuating said driving member so that its threaded nut cooperating with said screw moves said plunger forwardly and said shoulder head pushes forwardly coal dropped into said tube from said hopper and means for oppositely actuating said driving member so that its threaded portion cooperating with said screw moves said plunger rearwardly beyond where said hopper communicates with said tube so as to permit coal to drop from said hopper into said tube, said covered 40 plunger adapted to close communication between said hopper and said tube when said covered plunger is forward of said hopper, said covered plunger also adapted to prevent coal from entering its hollow interior at all times and clogging said screw.

EARL A. STRANG.
